CIRCUIT BREAKER

John G. Jackson, Detroit, Mich., assignor to
 Square D Company, Detroit, Mich., a corpora-
 tion of Michigan

Application April 24, 1933, Serial No. 667,696

22 Claims. (Cl. 200—116)

The invention relates to circuit breakers and has for its object the obtaining of a construction adapted for, first, automatically and effectively rupturing high values of current; second, selective 5 operation under various conditions of current flow. It is a further object to obtain a construction which will conform to the internationally accepted requirements of the National Board of Fire Underwriters and Underwriters Laboratories.

10 To this end the invention consists in various features of construction as hereinafter set forth.

One of the features of my invention is the means employed for suppressing the arc formed 15 on the breaking of contacts. For this purpose I make use of suppressor plates and magnetic deflection which have heretofore been used for such purpose. I have, however, designed a construction which is much more effective in its operation and which in addition to arc suppression protects 20 or guards against welding of the contacts and is exceedingly simple in construction.

Another feature of my invention is the means employed for selective operation. This comprises essentially an automatic circuit breaker, a 25 latch for holding the same normally in closed position, and a thermostatically operated releasing means for said latch adapted for substantially instantaneous operation in case of short circuiting and for operating with a small time 30 lag in case of relatively heavy overloads and for delayed operation in case of non-dangerous overloads. For instance where used to control a motor, an overload may be carried for a brief interval during starting of the motor without 35 releasing the latch but if continued for a longer period will effect the release.

My improved construction is adapted for various uses, but as specifically described and illustrated is a three-pole circuit breaker such as 40 adapted for use in connection with apparatus operating upon three phase electrical currents.

In the drawings:

Fig. 1 is a plan view of the switch with the cover of the housing removed;

45 Fig. 2 is a cross section on line 2—2 of Fig. 1;

Fig. 3 is a section on line 3—3 of Fig. 1;

Fig. 4 is an end elevation of the switch;

Fig. 5 is a similar view showing the parts in a different position of adjustment;

50 Fig. 5A is a sectional elevation illustrating the construction of bi-metallic thermostatic bars.

Fig. 6 is a section on line 6—6 of Fig. 1;

Fig. 7 is a perspective view showing the contact with magnetic deflector and the arc deflecting housing therefor removed;

55 Fig. 8 is a section through said contact and housing;

Fig. 9 is an elevation similar to Fig. 4 showing a modified construction;

60 Fig. 10 is a plan view of a portion of Fig. 9, and

Fig. 11 is a graph showing the characteristic curves respectively for the self-heating thermostatic element and the indirectly heated thermostatic element.

As shown, A is an insulator base plate for the circuit breaker on which are mounted the stationary contacts B, B', B² and the cooperating movable contacts C, C', C² which latter are carried by a rockable insulator member D pivotally mounted in a bracket E on the base A. A torsion spring F sleeved upon the pivot pin F' in the bracket E serves to resiliently hold the member D in open position. There is also a manually operable handle G pivotally secured upon a bracket G' connected by toggle links H, H' to a bracket H² on the rockable member D forming a means for closing the circuit and holding the contacts locked in closed position against the tension of the spring F.

For arc suppression and for guarding against welding of the stationary and movable contacts to each other, I have devised the following construction:

Each of the stationary contacts B, B', B² is formed of a bar of high electrical conductivity such as copper and preferably bent into substantially U form. The base portion B³ is secured to the base A and is provided with a connector clamping screw B⁴. The top portion B⁵ is parallel to the base B³ and has secured thereto a U-shaped member I of iron or other magnetic material having parallel legs I', I² and a comparatively narrow slot or space therebetween. Filling this space is an upwardly extending tongue B⁶ which is substantially flush with the upper face 35 of the member I and forms the contact face for bearing against the movable contact member C. The latter is also preferably formed of a flat bar of copper or other conductive material which is twisted to have an outer end portion C³ extending 40 in a vertical plane above the tongue B⁶ and a horizontal portion C⁴, the end of which rests upon the rockable member D. At the end of the portion C⁴ is a downwardly projecting tongue B⁷ engaging a recess in the member D to retain the 45 contact from lateral displacement and intermediate the ends of the member C is a spring J sleeved upon a pin J' which passes upward through the member D and bar C and has a detachable collar or abutment J² for the spring 50 at its upper end. The arrangement is such that in the closed position of the contacts the portion C⁴ will be at an oblique angle to the member D, the spring J being tensioned to hold the portion C³ against the portion B⁶. This also permits an 55 acceleration of the member D during opening movement before it lifts the contact C from the cooperating contact to impart an initial higher velocity thereto.

Mounted on the member B⁵ is a casing formed

of electrical insulator and heat resisting material and which comprises a pair of plates K K' parallel to each other on opposite sides of the portion C³ and above the portions I', I² of the member I. This casting is also provided with a portion K² which surrounds the member B⁵ and the end portion of the member I exposing only the portion B⁶. A spring clip K³ secured to the base A and embracing the casing serves to hold the same from displacement. Thus when the metallic circuit is broken by the separation of the member C from the tongue portion B⁶ the continued flow of current through the arc will develop a magnetic field which operates to deflect the arc outward between the plates K and K' and away from the member C³.

The tongue B⁶ may be formed of the same material as the member B but to avoid danger of melting and welding I preferably form this tongue of an electrically conductive but heat resistant material. Thus silver may be used for its high electrical conductivity and may be alloyed with some high fusing metal such as tungsten or molybdenum, or other similar metals. The small amount of material required for making the tongue will permit the use of such expensive metals without greatly adding to the cost of the structure.

As above stated, the contacts C, C', C² may be manually closed against the contacts B, B', B² by the operation of the handle G and when closed will be locked in this position by the straightening of the toggle links H H'. The automatic release of this lock under various conditions is effected by mechanism of the following construction:

Projecting from the base plate A are posts L, L', L², L³ on which are slidably mounted insulator blocks M and M'. N is a bar preferably of insulating material extending between the blocks M and M' and provided at its opposite ends with projecting fingers N³ which loosely engage bearings N⁴ on lugs M³ projecting from said blocks M and M'. The bar N passes beneath a bent link N' connected at one end to the common pivot of the links H and H' and at its other end having a hooked engagement with a pin N² on the post or bracket G', but yieldably held in engagement therewith by a spring N⁵. L⁴ are springs sleeved upon the posts L, L', etc. beneath the blocks M and M' acting to lift said blocks and through the medium of the connecting bar N to lift the bent link N' so as to break the toggle joint and permit the spring F to open the circuit breaker. Such operation is normally prevented by latch lugs for holding the blocks M and M' from upward movement and which are only released under certain conditions of current flow.

As above stated, the conditions under which the circuit breaker should operate are, first, in case of a short circuit and second, in case of an overload which is not objectionable for a short time interval but should not be carried for a longer period. For the performance of each of these functions I employ a thermostatic element which is heated to operating temperature by the excess current. However, for the first function the operation should be as nearly instantaneous as possible, while for the second function a definite time interval should elapse before release is effected. This I accomplish by placing the thermostatic element for the first function directly in circuit so that its ohmic resistance together with the increased volume of current will instantaneously generate heat for its operation. On the other hand, for the second function the heat

generated by the increased flow of current indirectly affects the thermostatic element so as to produce a lag of the desired duration.

Various constructions of thermostatic elements and latch locks may be employed, but as shown in Fig. 4 the construction is as follows:

O is a post projecting laterally from the block M and on which is revolvably mounted a toothed wheel O'. P and P' are bi-metallic thermostatic bars secured at their lower ends to the base A and extending upward on opposite sides of the toothed wheel O'. P² are shoulders formed upon the bars P, P' adapted to engage the diametrically opposite teeth of the wheel O' to hold said wheel from rotation in either direction and to also hold the block M in depressed position against the tension of the springs L⁴. One of the bi-metallic bars P' is directly connected into the electric circuit of one of the poles of the circuit breaker when the latter is in closed position. This circuit as shown comprises a conductor Q connecting the movable contact C with a post Q' passing through the base A and a conductor Q² connects the post Q' with a post Q³ passing upward through the plate A and connected to the base of the bi-metallic bar P'. The upper end of the bar P' is connected by a flexible conductor Q⁴ with a resistor conductor R arranged parallel to but out of contact with the bi-metallic bar P. The opposite end of the resistor R is connected to the terminal post R' through which the circuit breaker is connected into the external circuit.

With the construction just described, when the circuit breaker is in closed position current will flow from the stationary contact B to the movable contact C, thence through the conductor Q to the post Q'; through the conductor Q² to the post Q³ and bi-metallic bar P', then through the flexible conductor Q⁴ and resistor R to the terminal post R'. If the volume of current thus flowing is below a certain limit, the heat generated in the bi-metallic bar P' and resistor R will not be sufficient to produce a release. If, however, there is a short circuit, then the heat directly generated in the bi-metallic bar P' will cause the lateral deflection of said bar so as to release the shoulder P² from the toothed wheel O' whereupon said toothed wheel is permitted to revolve, disengaging from the shoulder P² of the bar P and permitting the springs L⁴ to lift the block M. This in turn will raise one end of the bar N, carrying upward with it the bent link N' so as to break the toggle joint and permit the spring F to open the circuit breaker. The volume of current required to produce this effect is relatively large and for lesser overloads the heat generated in the bar P' may not be sufficient to release said bar from the toothed wheel O'. However, the resistor R will generate heat by this limited overload which will be transferred by radiation or conduction to the bi-metallic bar P and after a definite time interval will warp said bar sufficiently to release the wheel O' from the shoulder P² whereupon the circuit breaker will open. Thus the two thermostatic elements P and P' are simultaneously affected by an overload but one will respond substantially instantaneously to a short circuit and with a small time lag to a relatively large overload above a predetermined limit without operative response below said limit, while the other will respond to an overload below said limit but with a greater time lag.

A modified construction is shown in Fig. 9. 75

This comprises the post O and toothed wheel O', thermostatic bi-metallic bar P and shoulder P² engaging one side of the wheel, the same as in the construction previously described. Instead, however, of providing a second bi-metallic bar upon the opposite side of the toothed wheel, a second toothed wheel S is arranged to engage the toothed wheel O'. This latter toothed wheel is fixed upon a pin S' which extends into a solder pot S² mounted upon a resistor T which is connected in to the electric circuit in series with a bi-metallic bar P. The resistor T is mounted upon posts U rising from the base A and so positioned as to hold the toothed wheel S in engagement with the toothed wheel O', while the pin S' is held from rotation by the solidified solder in the pot S². With this construction the operation under short circuit or excessive overload is the same as previously described, releasing the shoulder P² from the toothed wheel O' and permitting said wheel to turn so as to disengage from the toothed wheel S. For limited overloads, the shoulder P² will not be released from the toothed wheel O' but the heat generated in the resistor T will after a certain time interval melt the solder in the pot S², permitting the pin S' to revolve and with it the toothed wheel S. This will release the toothed wheel O' and effect the opening of the circuit breaker.

It is obvious that the specific constructions of latch releasing means above described may be variously modified. The essential feature is that the release is effected alternatively by a plurality of thermal means, one responding substantially instantaneously to a heavy overload, but providing a characteristically longer interval before tripping for lighter overloads, while the other is operated by a relatively light overload after a predetermined time interval which however differs from the characteristic operation of the first mentioned thermal means.

The arc suppressing means is exceedingly simple in construction and effective in operation. It will be noted that the U-shaped magnetic member is completely protected by the insulator housing and at the same time the legs of the U extend in fairly close proximity to each other. This will develop a strong magnetic field which reacts upon the arc to expel it in an outward direction away from the contacts C³ and B⁶.

The circuit breaker is preferably enclosed in a casing V, the cover of which is apertured for the passage of the manually operable handle G. The blocks M and M' are also provided with outwardly extending posts M² which pass through apertures in the cover and serve as means for re-setting the catch after the automatic release of the circuit breaker. When the catch is reset, the circuit closer may be closed by moving the handle G to the left, Fig. 2, from its dotted to its full line position. During this movement the link N' will hold the toggle links H H' from swinging upward so that the member D will be rocked to closed position and said links straightened and locked.

Fig. 11 is a graph illustrating the characteristics of the self-heating thermal unit by the curve Y and of the indirectly heated thermal element by the curve X. It will be noted that for a current volume of 44 amperes, the tripping of the circuit breaker will occur in the same time in each of these curves, viz: in 17½ seconds. For lesser current volumes, the element represented by the curve X will be the first to operate, but

for higher current volumes the element represented by Y will operate first. Thus for 120 amperes the element Y will release in one second, whereas the element X would require five seconds for release. Thus where both elements are used, the element X will be the first to operate up to 44 amperes and the element Y will be first for all higher current volumes.

The specific construction of switch shown and described is a three-pole switch and consequently it is essential to protect the circuits on each side of the central pole. For this reason the automatic releasing mechanism is in duplicate, one of said mechanisms responding to conditions in the circuit on one side of the central pole and the other responding to conditions in the circuit on the opposite side of said central pole. Either one of these mechanisms will throw the switch, as the lifting of one end of the bar N will actuate the link N' to break the toggle joint. Where, however, a two-pole circuit closer is used, a single releasing mechanism is all that is necessary.

What I claim as my invention is:

1. In a self-contained circuit breaker unit, the combination with fixed and movable contacts and resilient means for automatically separating the same, of means for restraining the operation of said automatic means to hold said contacts in closed position, and a plurality of releasing means for said restraining means, each comprising an electrically heated thermostatic element selected with respect to different overload current values, the thermostatic element responsive to the higher current value being self-heated thereby and the thermostatic element responsive to the lower current value being indirectly heated thereby to have a greater time lag in its operation.

2. In a self-contained circuit breaker unit, the combination with fixed and movable contacts and resilient means for automatically separating the same, of means for restraining the operation of said automatic means to hold said contacts in closed position, and a plurality of releasing means for said restraining means, each comprising a bi-metal thermostatic bar and one of said bars being in series circuit with said contacts and responsive to large overload current values, and a resistor in indirect heat communication relation to the other of said bi-metal bars, also in series circuit with said contacts and responsive to lower overload current values.

3. In a circuit breaker, the combination with fixed and movable contact members, of resilient means for automatically separating said members, a catch for restraining operation of said resilient means to hold said contact members in closed relation, said catch comprising a rotatable toothed wheel secured to the movable member and detents engaging teeth on the opposite sides of the axis of said wheel to restrain the same from either rotative or bodily movement, means responsive to different overload current values for withdrawing the detents on opposite sides of said wheel whereby the withdrawal of either detent will release said catch, and means for delaying the withdrawal of the detent by the means responding to the lower overload current value.

4. In a circuit breaker, the combination with fixed and movable contact members, of resilient means for automatically separating said members, a catch for restraining operation of said resilient means to hold said contact members in closed relation, said catch comprising a rotatable toothed wheel secured to the movable member and detents engaging teeth on the opposite sides of the

- axis of said wheel to restrain the same from either rotative or bodily movement, means responsive to different overload current values for withdrawing the detents on opposite sides of said 5 wheel, whereby the withdrawal of either detent will release said catch, the means responding to the higher current value consisting of a bi-metallic bar directly connected in series circuit with said contacts and the other of said means including a resistor and a thermostatic element indirectly heated thereby to have a predetermined lag in its operation.
6. In a circuit breaker, the combination with fixed and movable contact members, of resilient 10 means for automatically separating said members, a catch for restraining operation of said resilient means to hold said contact members in closed relation, said catch comprising a rotatable toothed wheel secured to the movable member and 15 detents engaging teeth on the opposite sides of the axis of said wheel to restrain the same from either rotative or bodily movement, a bi-metallic thermostatic bar connected to each detent and adapted to withdraw the same on the heating of 20 said bar to a predetermined temperature, means for connecting one of said bars in series circuit with said contacts to effect the heating of the bar by an overload current of large value, and an electrical heater also in series with said contacts 25 and in indirect heat communicating relation to the other of said thermostatic bars responsive to overload current of smaller value to cause withdrawal of the detent after a predetermined time 30 interval.
7. In a circuit breaker, the combination with fixed and movable contact members, of resilient means for automatically separating said members, a catch for restraining operation of said resilient means to hold said contact members in closed relation, said catch comprising a rotatable toothed wheel secured to the movable member and detents 35 engaging teeth on the opposite sides of the axis of said wheel to restrain the same from either rotative or bodily movement, means responsive to different overload current values for withdrawing the detents on opposite sides of said wheel whereby the withdrawal of either detent will release said catch, each of said means comprising a bi-metallic thermostatic bar to which the detent is attached, the bar in the means responding to the 40 higher current value being directly connected in series circuit with said contacts, and a resistor also in series circuit with said contacts in heat communicating relation to the other of said bars 45 to actuate the same with a predetermined lag.
8. In a circuit breaker, the combination with fixed and movable contact members, of resilient means for automatically separating said members, a catch for restraining operation of said resilient means to hold said contact members in closed relation, said catch comprising a rotatable toothed wheel secured to the movable member and detents engaging teeth on the opposite sides of the 50 axis of said wheel to restrain the same from either rotative or bodily movement, means responsive to different overload current values for withdrawing the detents on opposite sides of said wheel whereby the withdrawal of either detent will release said catch, the means responding to the higher current value comprising a bi-metallic thermostatic bar connected to the detent and in direct series circuit with said contacts, and the other of said means including a fusible connection with said detent and an electric heater in heat 55 communicating relation to said fusible member and included in series circuit with said contacts.
9. In a circuit breaker, the combination with fixed and movable contacts, of a rockable member carrying said movable contact, resilient means for automatically rocking said member to separate said contacts, manually operable means for rocking said member to close said contacts including a toggle jointed brace which locks in the closed position of the contacts, a resiliently operated trip for unlocking said brace to permit 60 automatic separation from said contacts, a catch for restraining said trip from operation including a toothed wheel revolvably mounted thereon, and detents for engaging teeth on opposite sides of the axis of said wheel to restrain the same from either rotative or bodily movement, and means responsive to different overload current values for respectively withdrawing the detents on opposite sides of said wheel, one of said means comprising a bi-metal thermostatic bar 65 directly connected in series circuit with said contacts, and the other of said means including a thermostatic element and an electrical heater in indirect heat communicating relation thereto, said heater being also included in series circuit with 70 said contacts.
10. In a circuit breaker the combination with fixed and movable contacts, of a rockable member for carrying said movable contact, resilient means for rocking said member to separate said contacts, manually operable means for rocking said member to close said contacts, said means including a toggle jointed brace for locking the contacts in closed position, a trip for said brace including a slidable block operatively connected thereto, resilient means for propelling said block, a catch for restraining said block from movement including a toothed wheel rotatively mounted on the block and detents engaging teeth on opposite sides of the axis of said wheel to hold the 75 same from either rotative or bodily movement, means responsive to different overload current values for respectively withdrawing said detents, one of said means including a bi-metal thermostatic bar attached to the detent and directly connected in series circuit with said contacts, and the other of said means including thermostatic means for withdrawing the detent, and an electrical heater in indirect heat communication therewith and also included in series circuit with said 80 contacts.
11. In a circuit breaker, the combination with fixed and movable contact members, of resilient means for automatically separating said members, a catch for restraining the operation of 85 said resilient means to hold said contact member in closed relation, said catch comprising a rotatable toothed wheel secured to the movable member and detents engaging the teeth of said wheel on opposite sides of the axis thereof to restrain the same from either rotative or bodily movement, means responsive to different overload current values for disengaging the detents on opposite sides of said wheel whereby the disengagement of either detent will release said catch, one 90 of said means comprising a bi-metallic thermostatic bar to which the detent is attached, said bar being directly connected in series circuit with said contacts, the other of said detents comprising a second toothed wheel, a shaft to which 95 said wheel is attached and a socket in which said shaft is secured by fusible metal, and an electric resistor connected in series with said contacts in heat conducting contact with said socket whereby cumulative heat from said re- 100

- sistor will fuse the metal in said socket and permit turning of said toothed wheels.
11. An electro-thermally released catch for automatic circuit breakers comprising a toothed wheel revolvably mounted on the movable member of said circuit breaker, a detent engaging a tooth on one side of said wheel, a second toothed wheel engaging the opposite side of said first toothed wheel, a shaft connected to said second toothed wheel, a socket for receiving said shaft, fusible metal in said socket for normally holding said shaft and toothed wheel from rotation, electro-thermal means responsive to a high overload for withdrawing said detent, and electro-thermal means responsive to a lower overload continued for a predetermined time interval for heating said socket to melt the fusible metal therein.
12. A self-contained circuit breaker unit comprising separable contacts and means for effecting automatic separation of said contacts, said means including a self-heated thermostatic element connected in series with said contacts, a resistor also connected in series with said contacts and a second thermostatic element heated by said resistor.
13. A self-contained circuit breaker comprising separable contacts and means effecting automatic separation of said contacts, said means including a self-heated bi-metal thermostatic bar connected in series with said contacts, a resistor also connected in series with said contacts and a second bi-metal thermostatic bar heated by said resistor.
14. A self-contained circuit breaker unit comprising separable contacts and means for effecting automatic separation of said contacts, said means including a self-heated bi-metal thermostatic bar connected in series with said contacts, a resistor also connected in series with said contacts and a second thermostatic element including a fusible holding means heated by said resistor.
15. A self-contained circuit breaker unit including separable contacts and a plurality of means for effecting automatic separation of said contacts, one of said means, responsive to large over-load currents, comprising a self-heated thermostatic element connected in series with said contacts and another of said means, responsive to sustained, lower over-load currents, comprising a thermostatic element indirectly heated by a resistor connected in series with said contacts and said first element.
16. A self-contained circuit breaker unit including separable contacts and a plurality of means for effecting automatic separation of said contacts, one of said means, responsive to large over-load currents, comprising a self-heated bi-metal thermostatic bar connected in series with said contacts and another of said means, responsive to sustained, lower over-load currents, comprising a bi-metal thermostatic bar indirectly heated by a resistor connected in series with said contacts and said first element.
17. A self-contained circuit breaker unit including separable contacts and a plurality of means for effecting automatic separation of said contacts, one of said means, responsive to large over-load currents, comprising a self-heated bi-metal thermostatic bar connected in series with said contacts and another of said means respon-
- sive to sustained, lower over-load currents, comprising a thermostatic element including a fusible holding means indirectly heated by a resistor connected in series of said contacts and said first element.
18. A self-contained circuit breaker comprising separable contacts and a plurality of means for effecting automatic separation of said contacts, one of said means comprising a self-heated, series connected thermostatic element operating 10 with moderate time lag in response to heavy over-loads and another of said means comprising a series connected resistor element and a thermostatic element indirectly heated thereby and operating in response to sustained, moderate 15 over-loads.
19. A self-contained circuit breaker comprising in combination separable contacts and a plurality of means for effecting automatic operation of said contacts, one of said means comprising a 20 self-heated thermostatic element having a time lag characteristic corresponding to the requirements for protection from heavy over-loads and another of said means comprising an externally heated thermostatic element having a time lag 25 characteristic corresponding to the requirements for protection from sustained moderate over-loads.
20. In a three-pole circuit breaker, the combination of separable contacts, resilient means for 30 automatically separating contacts, manually operable means for closing said contacts and holding them in closed position and a releasing device for said holding means comprising a plurality of current responsive units connected to 35 different poles of said breaker, each of said units comprising a plurality of thermostatic means, one of said thermostatic means comprising a self-heated, series connected thermostatic element and another of said thermostatic means 40 being indirectly heated by a series connected resistor element.
21. A self-contained circuit breaker equipped for circuit and motor protection comprising in combination separable contacts and a plurality 45 of means for effecting automatic separation of said contacts, one of said means comprising a self-heated thermostatic element having a time lag and current characteristic corresponding to the requirements for circuit protection and another of said means comprising an externally heated thermostatic element having a time lag 50 and current characteristic corresponding to the requirements for motor protection.
22. In a self-contained circuit breaker unit 55 equipped for circuit and motor protection, the combination with fixed and movable contacts and resilient means for automatically separating the same, of means for restraining the operation of said automatic means to hold said contacts in 60 closed position, and a plurality of releasing means for said restraining means, each comprising an electrically heated thermostatic element selected with respect to time lags at different current values, the thermostatic element for circuit protection, responsive to the higher current values, being self-heated thereby and the thermostatic element for motor protection, responsive to the lower current values, being indirectly heated thereby to have a greater time lag in its opera- 65 70
